J. BRYERS

WRENCH

Filed June 17, 1924

Joseph Bryers

Watson E. Coleman
Attorney

UNITED STATES PATENT OFFICE.

JOSEPH BRYERS, OF HAVRE, MONTANA.

WRENCH.

Application filed June 17, 1924. Serial No. 720,589.

To all whom it may concern:

Be it known that I, JOSEPH BRYERS, a citizen of the United States, residing at Havre, in the county of Hill and State of 5 Montana, have invented certain new and useful Improvements in Wrenches, of which the following is a specification, reference being had to the accompanying drawings.

This invention relates to improvements in 10 wrenches and has for an important object thereof the provision of a novel and improved adjustable jaw wrench.

A further object of the invention is to provide in an adjustable jaw wrench a 15 ratchet mounting for the jaws so that they may be rotated about a center without the necessity of disengaging them from the work.

A still further object of the invention is 20 to provide a device of this character which may be very cheaply and readily produced, which will be durable and efficient in service and a general improvement in the art.

These and other objects I attain by the 25 construction shown in the accompanying drawings, wherein for the purpose of illustration is shown a preferred embodiment of my invention and wherein:—

Figure 1 is a plan view of a wrench constructed in accordance with my invention, 30 a portion of the wrench handle being broken away;

Figure 2 is a section on the line 2—2 of Figure 1;

Figure 3 is a section on the line 3—3 of Figure 1;

Figure 4 is a perspective of one jaw of the wrench;

Figure 5 is a perspective of the second jaw 40 of the wrench;

Figure 6 is an inverted perspective of the last named jaw.

Referring now more particularly to the drawings, the wrench includes a pair of 45 opposed jaws 10 and 11, these jaws having coacting extensions 12 and 13 respectively, each of these extensions being of less thickness than the jaw by which it is borne and being arranged at one side of the jaw, the 50 jaws being notched, as at 14, to provide surfaces forming continuations of the extensions. The extension 12 is provided with a central upstanding rib 15 fitting in a similar groove 16 formed in the extension 13. The 55 upper surface of the rib 15, the bottom surface of the groove 16, and the surfaces of

the extensions 12 and 13 and their continuations formed by the notching of the jaws are provided with coacting serrations 17 which, when the faces of the extensions are 60 forced into engagement one with the other, prevent any relative longitudinal movement and maintain the jaws 10 and 11 in parallel relation and in adjusted position.

Each extension 12 and 13 has formed 65 therethrough a longitudinally extending slot 18, these slots combining for the reception of a squared bolt 19 having a head 20 abutting the under surface of the extension 12 and having a length greater than the combined thicknesses of the extensions. The bolt is provided at the end of the squared shank thereof with a threaded extension 21 for a purpose presently to appear. The numeral 22^a designates a handle having rotatably 70 mounted therein at one end thereof a head 22 circular in form and provided on its periphery with a pair of ratchets 23 having oppositely facing teeth. The handle provides a pivotal mounting for a compound 75 dog 24 one lug 25 of which coacts with one of the ratchets 23 and the other lug 26 coacts with the other of the ratchets, the ratchet engaged depending upon the position of the dog in which is mounted a spring 80 27 engaging the tail of the dog.

The head 22 has an axial bore 28 one end of which is squared for the reception of the squared shank of the bolt, as indicated at 29, and the other end of which closely 90 fits the threaded extension 21 of the bolt. This threaded extension is engaged at the opposite side of the head from the squared portion of the bore by a thumb-screw 30 for applying strain to the bolt. One of the extensions, at present shown as the extension 12, has formed in its surface coacting with the other extensions sockets 31 in which are mounted springs 32 engaging the face of the other extension and tending to separate 100 the extensions at all times. It will be obvious that if the bolt 19 is released by the thumb-screw these springs will tend to force the faces of the extensions of the jaws out of engagement so that the jaws are freed 105 for longitudinal movement. The depth of the teeth 17 of these jaws being such that separation of the teeth is accomplished before the rib 15 is withdrawn from the slot 16 so that the jaws are maintained in alignment. With the jaws in separated relation 110 they may be adjusted to proper position and

locked in such position by tightening the thumb-screw 30. By manipulating the ratchet the engaged work may be rotated in either direction as desired.

5 It will be obvious that the engagement of the shank of the bolt in the squared opening of the head 22 will tend to prevent relative rotation of the head with the jaws. In order to further assist in preventing such 10 relative rotation, since the strain upon the bolt would be considerable, I provide upon the under surface of the head a diametrically extending rib 33 engaging in a groove 34 formed upon the adjacent surface of the 15 jaw 11 and its extension 13.

It being obvious that certain changes in the construction are possible without in any manner departing from the spirit of my invention, I do not limit myself to such 20 specific structure as hereinbefore set forth except as hereinafter claimed.

I claim:—

1. In a wrench, a pair of parallel jaws, said jaws having overlapping extensions 25 provided upon coacting faces thereof with serrations interengaging to maintain the jaws in fixed relation, said extensions being each provided with a longitudinally extending slot, a squared shank bolt directed 30 through said slot, a head with which the squared shank bolt engages, means at the opposite side of the head from the jaws for drawing the bolt into the head to clamp the jaws together against the head, and means for separating the coacting faces of the 35 extensions when the last named means is released.

2. In a wrench, a pair of parallel jaws, said jaws having overlapping extensions 40 provided upon coacting faces thereof with serrations interengaging to maintain the

jaws in fixed relation, said extensions being each provided with a longitudinally extending slot, a squared shank bolt directed through said slot, a head with which the squared shank bolt engages, means at the opposite side of the head from the jaws for drawing the bolt into the head to clamp the jaws together against the head, and means for separating the coacting faces of the extensions when the last named means is released, one of said extensions having a rib extending into a slot of the other of said extensions and of greater height than the depth of the serrations of the jaws. 45

3. In a wrench, a pair of parallel jaws, said jaws having overlapping extensions provided upon coacting faces thereof with serrations interengaging to maintain the jaws in fixed relation, said extensions being each provided with a longitudinally extending slot, a squared shank bolt directed through said slot, a head with which the squared shank bolt engages, means at the opposite side of the head from the jaws for drawing the bolt into the head to clamp the jaws together against the head, means for separating the coacting faces of the extensions when the last named means is released, one of said extensions having a rib extending into a slot of the other of said extensions and of greater height than the depth of the serrations of the jaws, a handle engaging said head and rotatable thereon, said handle engaged portion of said head being provided with a pair of ratchets having oppositely directed ratchet teeth the handle having a dog selectively engageable with said ratchets. 50

In testimony whereof I hereunto affix my signature.

JOSEPH BRYERS.
